UNITED STATES PATENT OFFICE.

CHARLES H. SCHURR AND ERNEST J. LEES, OF CLEVELAND, OHIO, ASSIGNORS TO THE
LEES BRADNER COMPANY, OF CLEVELAND, OHIO.

METHOD OF CUTTING A WORM.

1,243,767.

Specification of Letters Patent. Patented Oct. 23, 1917.

Application filed November 5, 1914. Serial No. 870,393.

To all whom it may concern:

Be it known that we, CHARLES H. SCHURR and ERNEST J. LEES, both citizens of the United States, residing at Cleveland, in the 5 county of Cuyahoga and State of Ohio, have invented a new and useful Improvement in Methods of Cutting Worms, of which the following is a specification, the principle of the invention being herein explained and the 10 best mode in which I have contemplated applying that principle, so as to distinguish it from other inventions.

Our invention relates, more particularly than its title indicates to a method of generating a worm of absolutely precise predetermined pitch line form, whereby the product is adapted to constitute a coöperating or truly mating part for the transmission of power with consummate nicety of operation. 15 We fulfil the desired object by establishing between the work and a cutter, a manufacturing relation which is precisely similar to the relation it is desired to present between the coacting units of what is commonly known as a "worm drive". A cutting tool is presented to the work in precisely the manner and direction that the spaces between the teeth are to be intersected by such surfaces as are to engage the working surfaces 20 of the threads. The configuration at the pitch line is the factor upon which the efficiency depends.

The distinguishing features of our invention are four in number, viz:

- 35 1. Fixed center distance.
2. Tangential relation of worm axis.
3. Cutting in a parallel plane.
4. Cutter having a transverse motion.

The drawings exemplify in Figure 2 a 40 worm drive of the side engagement type so that the worm engages the mating member by intersection in the direction parallel to the axis of the latter, and in Fig. 1 they exemplify a resort to an end mill to accomplish the cutting operation.

Fig. 1 shows end mills of conical surface, whereas Figs. 7 and 8 show the coaction and result respectively of a unit of cylindrical outline.

45 The inventive conception is associated with means which are hereinafter explained and variously combined in the claims. While the annexed drawings and particular description thereof, set forth an arbitrarily

preferred and one modified form based upon 55 our invention, it should be understood that such means only exemplify two of many diversified mechanical forms with which the principle of our invention may be properly applied.

50 Fig. 1 is a diagrammatic view showing the manner in which our invention may be practised.

Fig. 2 is a section on line X—X of Fig. 1 looking in the direction of the arrows and 65 showing the manner in which the worm is employed as a lateral drive.

Fig. 3 is a diagrammatic view of a single cutter seen looking in the opposite direction to that of Fig. 2.

70 Fig. 4 is a section on line Y—Y of Fig. 3.

Fig. 5 is a section on line Z—Z of Fig. 3 looking downwardly.

75 Fig. 6 is a vertical axial section of the worm gear seen in Fig. 3.

Fig. 7 is a view corresponding to Fig. 4 showing the application of a cutter of modified outline.

80 Fig. 8 is a view corresponding to Fig. 6 and pertaining to the product resulting from the employ of such a modified tool.

Adverting to Fig. 1, it will be noted that only so much has been drawn as will indicate to one sufficiently skilled in the art how the required movements are carried out. A 85 driving member 1 to be considered as connected with a source of power, serves to rotate in proper ratio both the work 2 through the agency of a gear 3, and the tool disk 4 through the agency of a gear 5 keyed there- 90 to at 6. The independent rotation of the end mills 7 simultaneously with their revolving action is effected by transmission of power from gear 8 to gear 9 to shaft 10, to gear 11, to pinions 12 and thus to the individual splined tool shafts 13. The proper feed or movement of the shafts 13 in the parallel directions of their axes will be presumed as imparted to the circumferential series of tools by means of the spline connec- 95 tions, such that owing to what is in effect an approach toward and recession from the axis of the work, the thread develops shallower toward the ends and at the same time gradually thicker at the top. In other 100 words such development is owing to the arc of movement seen in Fig. 3. Such arc meets

105 with the axis of the work at its middle so

that such axis is tangential thereto. Fig. 2 nicely shows the tangential relation of the axis of the worm to the cylindrical surface generated by an axis of a cutter.

5 The type of cutter 7 which has been arbitrarily chosen as preferred for the exemplifying purpose of Figs. 1, 4, and 5 is conically surfaced and produces a worm such as is shown in Figs. 2 and 3. Such outer surface or outline of the cutter or end mill 7 would in practice correspond to the outlines of circumferentially arranged beveled rollers or truncated conical rolls such for example as were shown described and claimed 10 in a joint application of R. H. Rosenberg and Ernest J. Lees filed November 15, 1912, Serial No. 731,518. It will be noticed in Figs. 3 and 6 that the root 14 develops as an arc depressed toward the axis, the tops of 15 the teeth lying in a straight line. In Fig. 20 5 as viewed, it is furthermore made clear that the completed cut is perfectly true both with the root and side faces whereby the latter taken on the pitch line conform to the outline of the end mill which has in turn been premised as conforming to the working faces of the worm gear with which the worm is to roll. The top of the thread in such Fig. 5 is disposed in an arc because 25 the blank is a true cylinder, whereas the roots in this figure owing to the fact that it is a developed projection appear to lie in a straight line parallel to the axis. The pitch line is caused to follow or be parallel with 30 the bottom.

It should be understood from the claims 35 that this method is independent of a fixed type of cutting tool as it is also of the operation of an end mill of definitely prescribed 40 shape, and to demonstrate this we have added in Fig. 7 a view of a cutter 7^a of cylindrical as distinguished from conical outline. Such a cutter would produce a worm whose 45 axial section is depicted in Fig. 8, wherein 50 it will be seen that the roots 16 of the teeth lie in an arc. The tops 17 in this instance also lie in an arc either because the blank was so formed in the beginning or because 55 the cutter carried side edges capable of 60 reaching and trimming the tops. The faces 18 of the product shown in Fig. 8 furthermore differ from the faces of the teeth seen in Fig. 6 in that they are perpendicular to the axis, while those in Fig. 6 are inclined 65 relative to the axis. This method necessitates cutters slightly larger than the outline of the rollers or other working faces, with which our worm product is to roll. Otherwise opposed rolling actions on both sides 70 of the assumed rollers with a hindering friction would ensue. In the case of the conical end mill the "in and out" adjustment compensates sufficiently to avoid this happening, since it depends merely on how far such 75 tool is set in.

For the purpose of avoiding confusion in the interpretation of the claims, three certain planes each of which is perpendicular to the other two will be specified and identified arbitrarily by name as follows:—

(a) The plane of the generating circle should be assumed as vertical and in the claims is consistently referred to as the "vertical plane." Such happens to be also, according to the drawings, the plane of rotation of the cutters. 70

(b) The plane to which the axis of the work is perpendicular, or what is the same thing, the plane of gear 3, will be consistently called the "transversely vertical plane." 80

(c) That axial plane of the worm or work which is perpendicular to the generating plane shall be considered as the "horizontal plane." 85

We claim:—

1. The method of cutting a worm which consists in effecting cuts from the work along an arc of movement corresponding to that described by the working faces of a 90 gear wheel with which the worm is to roll, establishing a fixed distance between the centers of the working units and feeding in a direction at an angle to the plane of the generating circle. 95

2. The method of cutting a worm which consists in rotating the work and simultaneously rotating and revolving a cutter in engagement with such work, the axes of said cutter and work being disposed at right angles, and feeding said cutter in a direction parallel to its own axis. 100

3. The method of cutting a worm which consists in rotating the work, rotating a cutter in proper ratio to and in operative engagement with said work, revolving the cutter in a plane parallel to one axial plane of the work, and feeding the cutter axially parallel to another axial plane of the work. 105

4. The method of cutting a worm which 110 consists in rotating the work, rotating and revolving a cutter in proper ratio and in operative relationship to the work, and constantly feeding the cutter transversely to the generating circle. 115

5. The method of cutting a worm which consists in rotating the work, revolving a series of cutters in predetermined operative relationship to the work, simultaneously rotating said cutters, and feeding the latter transversely to the generating plane thereof. 120

6. The method of cutting a worm which 125 consists in rotating the work, simultaneously revolving and rotating a cutter in engagement therewith and constantly feeding the cutter axially of itself.

7. The method of cutting a worm which consists in rotating the work, rotating a cutter, effecting between the work and cutter an operative engagement, the axes of said 130

cutter and work being constantly disposed at right angles, and simultaneously feeding said cutter axially.

8. The method of cutting a worm which consists in rotating the work in operative proximity to a cutter, revolving the cutter in a plane parallel to one axial plane of the work, and feeding the cutter parallel to a transverse axial plane of the work.
- 10 9. The method of cutting a worm which consists in rotating a work piece, revolving a

series of cutters in engagement therewith, and simultaneously feeding the said series of cutters in the same direction.

Signed by us, this 4th day of November, 15
1914.

CHARLES H. SCHURR.
E. J. LEES.
